UNITED STATES PATENT OFFICE.

THOMAS N. EATMAN, OF HAIRSTON, ALABAMA.

ALARM DEVICE.

1,182,539.

Specification of Letters Patent.

Patented May 9, 1916.

Application filed September 24, 1915. Serial No. 52,434.

To all whom it may concern:

Be it known that I, THOMAS N. EATMAN, a citizen of the United States, residing at Hairston, in the county of Greene and State 5 of Alabama, have invented new and useful Improvements in Alarm Devices, of which the following is a specification.

This invention relates to alarm devices by means of which audible signals will be given 10 upon the level of the liquid lowering a predetermined degree.

The primary object of the invention is to provide a device of this character wherein the parts are readily separated for obvious 15 reasons.

Another object of the invention is the novel manner of mounting the switch mechanism within the cylinder so that the same can be readily inserted in the latter while 20 at the same time being protected from the liquid.

The invention consists in the features of construction, combination, and arrangement 25 of parts, hereinafter fully described and claimed, reference being had to the accompanying drawings, in which:

Figure 1 is a vertical section through the device. Figs. 2 and 3 are cross sections on the line 2—2 and 3—3 of Fig. 1.

Referring to the drawings, the numeral 1 designates a cylinder, the lower end of which being adapted to communicate with a body of liquid, while the upper end has threaded thereon a cap 2 having a centrally 35 arranged aperture 3 in which is threaded a packing gland 4 for a purpose hereinafter described.

Frictionally held within the cylinder at a spaced point from the cap 2 is a disk 5 also provided with a central aperture 6 passing through the cylinder and entering the periphery of the disk 5 are screws 7 for rigidly holding the disk in place and to allow the same to be readily removed at will. From 45 this construction it will be seen that a chamber 8 is formed. Arranged in this chamber 8 is a switch mechanism 9 comprising a switch arm 10 pivotally connected as shown at 11 to a bracket 12 of insulating material. 50 Also secured to the bracket 12 is a contact finger 13 having a curved extremity 14 arranged to engage the switch arm 10 when

the latter is lowered against the action of a coil spring 15 arranged between the arm and the upper surface of the disk 5. For moving the switch arm 10 downwardly as the level of the liquid lowers, I provide a float 16 having connection with the arm by means of the sleeves 17 threadedly mounted upon a rod 18 that in turn has a pin and slot connection 19 with the arm. The switch arm 10 and the contact finger 13 are arranged in an alarm circuit 20.

From the foregoing description, it will be seen that when the level of the liquid lowers 65 a predetermined degree, the arm 10 will be thrown into electrical engagement with the contact finger 13 for closing the alarm circuit.

Attention is called to the fact that by removing the screws 7 and the screws 21 that support the bracket of insulating material, the float, rod, and switch mechanism can be removed as a unit.

For giving a visual indication as to the 75 level of the liquid I provide a sight glass 22 communicating at its upper and lower end respectively with the upper and lower portion of the cylinder and the same has thereon graduation marks 23. Movable within 80 the sight glass 22 is a float 24 which moves in accordance with the raising and lowering of the column of liquid.

Having described my invention, what is claimed is:

A circuit closer comprising a cylinder, a cap threaded upon one end of said cylinder, a disk detachably mounted in said cylinder at a point spaced from said cap, a bracket of insulating material secured to said cylinder 90 between said cap and disk, a contact finger secured to said bracket, a switch arm pivotally connected at one end to said bracket, a coil spring arranged between the remaining end of said arm and said disk, a float having 95 a pivotal connection with the intermediate portion of said arm.

In testimony whereof I affix my signature in presence of two witnesses.

THOMAS N. EATMAN.
